UNITED STATES PATENT OFFICE.

NEWTON J. TATE, OF WEATHERFORD, TEXAS, ASSIGNOR TO THOMAS HARRIS COULTER, OF SAN ANTONIO, TEXAS.

WIRE-WORKING TOOL.

SPECIFICATION forming part of Letters Patent No. 769,879, dated September 13, 1904.

Application filed March 6, 1902. Serial No. 96,931. (No model.)

To all whom it may concern:

Be it known that I, NEWTON J. TATE, a citizen of the United States, residing at Weatherford, in the county of Parker and State of Texas, have invented certain new and useful Improvements in Wire-Working Tools, of which the following is a specification.

My invention relates to wire-working tools of the type represented in Letters Patent No. 667,854, granted to me February 12, 1901, and on which the present device is an improvement.

My patented device has been found in practice to be defective in certain particulars and 15 to be inadequate for the performance of certain operations which constantly arise during the handling of wire in constructing fences and the like. For instance, in this class of work it frequently becomes necessary during the 20 twisting together or stretching of the wires to securely hold the free end or ends of one or more wires while the loop of a folded wire is in engagement with the wire-engaging hook, this being particularly true in the twisting of 25 a wire which has been folded back and forth upon itself to produce a three or four strand brace, which operation cannot under said circumstances be performed by my patented device.

30 The present invention has for its objects to produce a simple inexpensive tool which in practice will be entirely free from the above-mentioned objections and defects, thereby meeting the various conditions arising in the 35 handling of the wire.

To these ends the invention comprises the novel features of construction and combination of parts more fully hereinafter described.

In the accompanying drawings, Figure 1 is 40 a side elevation of my improved device, showing the same closed. Fig. 2 is a similar view with the pliers open. Fig. 3 is a bottom plan view. Fig. 4 is a detail rear end view.

Referring to the drawings, it will be seen 45 that my improved device comprises a primary handle member A and a secondary handle member B, crossed adjacent to their front ends and pivoted together, as at G, said members being provided, preferably in advance of the

pivot, with co-operating toothed portions or 50 jaws H H', constituting wire-engaging pliers.

The primary member A is provided in advance of the plier-jaws with a forwardly-extending cylindrical portion J, terminating at its forward end in an eye K, pivotally engaged 55 by a wire-engaging device or hook L.

Swiveled upon the cylindrical portion J is a sleeve or collar M, formed upon and carrying a forwardly-extending post-engaging finger or member N, extending parallel with the 60 longitudinal axis of the tool and provided at its outer end with a sharpened post-engaging spur or tip N'.

A pair of holes O O are provided, respectively, in the handles A B adjacent to their 65 pivotal point, and a similar hole P near the outer end of the handle B, these openings being designed to receive the wire under certain conditions which may arise during the manipulation of the latter. Furthermore, one of the 70 handles may be provided with a claw Q and the other with a screw-driver R, a punch S being disposed and sustained between the handles, these features of the tool constituting, however, no part of my invention. 75

In practice if it is desired to stretch a wire having its end looped the latter is engaged with hook L and the finger N with the post for performing the stretching operation, while, on the other hand, if a single wire is to be 80 stretched its end may be engaged and held by the pliers during the stretching operation, or in the case of a wire folded upon itself to form three strands the loop in the wire is engaged with the hook and the adjacent free end of the 85 wire by the pliers. During the operation of twisting wires in forming braces, &c., the looped portions of the wires are engaged with the hook and the free ends of the wires with the pliers in a manner similar to that just 90 described in connection with the stretching operation.

From the foregoing it will be seen that I produce a simple inexpensive device which is admirably adapted for the attainment of the 95 ends in view, it being understood, however, that I do not limit myself to the precise details herein set forth, inasmuch as minor

changes may be made without departing from the spirit of the invention.

Having thus described the invention, what is claimed is—

5 In a wire-working tool, the combination with a pair of members pivotally connected, of coöperating jaws provided on the members and constituting wire-engaging pliers, a forwardly-extending post-engaging member

swiveled to one of said members in advance of the pliers, and a wire-engaging device also carried by one of said members.

In testimony whereof I affix my signature in presence of two witnesses.

NEWTON J. TATE.
